LUGGAGE CARRIER

William C. Baxter, Portland, Oreg.

Application February 26, 1957, Serial No. 44,998

Term of patent 14 years

(Cl. D14—27)

Figure 1 is a perspective view of a luggage carrier showing my new design.

Figure 2 is a perspective view with the cover in open position.

The portions of an automobile shown in broken lines are for purposes of illustration only.

I claim:

The ornamental design for a luggage carrier as shown and described.
